UNITED STATES PATENT OFFICE.

ALFRED E. LEFIELD, OF SAN FRANCISCO, CALIFORNIA.

AUTOMATIC SPACER FOR SMOKEHOUSE TROLLEYS.

Application filed April 27, 1928. Serial No. 273,423.

This invention relates to means for automatically spacing hams and bacon on a smokehouse trolley or hanging frame.

The principal object of the invention is to 5 provide means whereby the hams and bacons to be hung upon the racks will be equally spaced, and to further provide means whereby the same cannot be accidentally removed.

10 A further object is to produce a device of this character which is economical to manufacture, and one which conforms to the standard practise employed in smokehouses.

15 A further object is to produce a device of this character wherein the cord supporting the hams will not be easily cut.

A still further object is to provide a structure which is simple and neat in appearance.

20 Other objects and advantages will be apparent during the course of the following description.

25 In the accompanying drawings forming a part of this specification and in which like numerals are employed to designate like parts throughout the same,

Figure I is a perspective view of a trolley rack constructed in accordance with my invention,

30 Figure II is an enlarged side elevation of Figure I, with the hangers removed,

Figure III is an enlarged detail fragmentary view of a portion of the rack, and

Figure IV is a cross-section taken on the line 4—4 of Figure III.

35 At the present time trolley racks are employed in smokehouses, many of which are oval in construction and consist of a bar so formed and having pegs upstanding therefrom, or indentations cut in the edge 40 thereof. The string of the ham, which string is in a loop form, is hung over these pegs, generally around two pegs and by skipping every other set of pegs, the hams will be properly spaced.

45 The operators however oftentimes become careless in placing the hams upon the racks with the result that if every other place is not skipped, the hams will be too close together, and will touch each other and therefore will not be properly cured.

I have therefore devised means whereby the same rack may be employed for either hams or bacons, and have further provided means whereby it is impossible to hang the 50 hams closer than the desired spaces, and at

the same time permitting as many bacons to be mounted on the rack as desired.

In the accompanying drawings wherein for the purpose of illustration is shown a preferred embodiment of my invention, the 60 numeral 5 designates a bar which may be straight or formed into a rectangular shape as shown in Figure I, which bar is provided along its upper edge with notches 6 and 7. Upon one side of the bar and adjacent the 65 notches 6, I place hooks 8 which hooks have down-turned ends as shown at 9 (see Figure IV).

The result of this construction is that 70 when the ham string is hung over the notch 6, it will be wrapped around the hook 8 which will hold the ham in place. If the operator attempts to place the string through the slot 7 there would be no way of holding 75 the string as no hooks are formed adjacent the slots 7. It therefore follows that the operator can only hang a ham in the slots 6, resulting in an automatic spacing of the hams.

The bacons are hung upon hooks in parallel relation. As the bacons are of slab formation they may be hung relatively close together, and yet will have sufficient space therebetween to receive a proper curing. As hooks are employed for the bacon, it is 85 obvious that the slots 6 and 7 will serve to properly space them. The hooks 8 are not necessary to their hanging.

It will thus be seen that I have provided 90 a very simple device for accomplishing all the objects herein set forth.

It is to be understood that the form of my invention herewith shown and described is to be taken as a preferred example of the same, and that various changes relative to 95 the shape, size, material and arrangement of parts may be resorted to without departing from the spirit of the invention or the scope of the subjoined claims.

Having thus described my invention, I 100 claim:

1. An automatic spacing device for supporting hams, bacons and the like comprising a bar having a plurality of notches formed therein and spaced one from the other, hooks secured to said bar, each of said hooks being positioned in proximity to each alternate notch and a cord for supporting each ham, bacon or the like, being trained through each alternating notch and con- 110

nected to said hook whereby the articles are spaced one from the other and contact of said articles is prevented.

2. An automatic spacing device for supporting hams, bacons and the like comprising a substantially rectangular frame having a plurality of notches formed therein and spaced one from the other, a plurality of hooks secured on the inner surface of said

frame, each of said hooks being positioned in proximity to each alternate notch and a cord for supporting each ham, bacon or the like being trained through each alternating notch and connected to said hook whereby the articles are spaced one from the other and contact of said articles is prevented.

In testimony whereof, I affix my signature.

ALFRED E. LEFIELL.
